UNITED STATES PATENT OFFICE.

JOHN A. SEELY, OF OGDENSBURG, NEW YORK.

STEERING MECHANISM.

1,055,814.

Specification of Letters Patent. Patented Mar. 11, 1913.

Application filed January 22, 1910, Serial No. 539,534. Renewed January 4, 1913. Serial No. 740,237.

To all whom it may concern:

Be it known that I, JOHN A. SEELY, a citizen of the United States, residing at Ogdensburg, in the county of St. Lawrence 5 and State of New York, have invented new and useful Improvements in Steering Mechanism, of which the following is a specification.

My invention relates to certain new and 10 useful improvements in steering mechanism, and relates more particularly to a steering mechanism for motor boats.

The object of the invention is to provide 15 a steering mechanism of this character in which the steering wheel will embody a spark control and a gas control or throttle.

A further object of the invention is to 20 generally improve and simplify, and at the same time to lessen the cost of manufacture 25 and increase the efficiency of mechanisms of this type, and to provide an improved type of holding means for the steering mechanism itself.

Further and other objects will be later 30 set forth and of themselves evidenced.

In the drawings: Figure 1 is a side elevation, showing some of the parts broken away and in section, of the improved device, Fig. 2 is a fragmentary section taken longitudinally through the lower end of the device as shown in Fig. 1, Fig. 3 is a section taken on line 3—3 of Fig. 2, Fig. 4 is a perspective view of one of the brackets which support the steering device in position, Fig. 5 is a front elevation of one of the brackets, Fig. 6 is a view similar to Fig. 3 of a modified form of the invention, Fig. 7 is a front elevation of the modified form showing the upper part of the steering mechanism removed, Fig. 8 is a section on line 8—8 of Fig. 6, and Fig. 9 is a fragmentary top plan view of the steering wheel proper showing the spark and gas control levers. Fig. 10 is a sectional view of a modified form of one of the brackets for supporting the modified form of steering device.

The invention as at present contemplated includes a base plate 1, on each end of which 50 is mounted curved guiding blocks 2, the latter being adapted to engage chain 27. Preferably formed integral with the base plate 1, and depending therefrom is a collar 3, the collar being interiorly threaded 55 so as to be in threaded engagement with the

arbor tube 4. A bearing sleeve 5 is secured in the lower end of the arbor tube 4 by means of a screw 6 which passes through collar 3, arbor tube 4, and extends partly into the sleeve 5, as shown in Fig. 2, whereby the arbor tube 4 is held rigid, with the bearing sleeve 5, which latter forms a bearing for the lower end of the longitudinal control handle tube 7. Fitted to rotate within the tube 7 is a second longitudinal 60 control handle rod 8. A control foot 9 is secured to the tube 7 so as to rotate therewith, and a similar control foot 10 is secured to the rod 8 so as to partake of the movements thereof, it being understood that 65 these control feet govern the spark, that is to say, one of the feet controls the spark and the other controls the gas, the spark control being for the purpose of advancing and retarding the spark and the gas control or throttle that of the gas, as is understood by those versed in the art of gas engines.

A sprocket wheel 11 surrounds the stationary arbor tube 4, and is rotatable with 80 respect thereto, the sprocket wheel being formed with an upwardly extending externally threaded annular flange 12, which is in threaded engagement with the outside tube 13, the upper end of tube 13 rigidly carrying the steering wheel 14. A common sector 15 is rigidly carried by the steering wheel 14 and is provided on its opposite sides with depressed seats 16 as seen in Fig. 9. A lever 17 is rigidly secured to the upper 85 end of rod 8 and is formed in its outer end with a hollowed out portion in which a small coil spring 18 is mounted, the outer end of the coil spring exerting pressure against a ball 19, which latter is adapted to 90 engage in one of the seats 16, it being understood that the pressure of the spring 18 can be readily overcome by manual movement imparted to the lever 17. Similarly a second lever 20 is rigidly secured to the upper 95 end of the tube 7, lever 20 being equipped with a similar spring pressed ball which latter however engages the seats 16 formed in the periphery of the sector 15, as distinguished from the spring pressed ball of 100 the lever 17 which engages the seats in the inner surface of the sector 15. By reference to Fig. 2 it will be observed that the base plate 1 is formed with downwardly extending 105 perforated ears 21, which latter are 110

adapted to be received in the bifurcated end 25 carried by the arm 23 of the bracket member 24. As shown in Fig. 1 of the drawings bracket 24 is suitably secured to the front 5 board of the boat in any approved manner, and the bifurcated end 25 is formed with a perforation adapted to align with the perforation in ear 21, a securing thumb screw 26 being passed through the alining perforations whereby the furcations may be 10 clamped into engagement with the ears 21 to thereby hold the steering mechanism in any desired angular position, one of the positions being illustrated in Fig. 1 of the 15 drawings.

A chain 27 engages with sprocket 11 and between the flanges of the guide rollers 2, the chain having its ends connected with the rudder in a manner well known and familiar to those versed in the art. 20

A modification is illustrated in Figs. 6, 7, 8 and 10, in which the base plate 1 is provided with curved bearing blocks 2' and lugs 2' which together serve as a means 25 to support the cover plate 4'. In this form of the invention the base plate is cast or otherwise formed with hollow turnnions 3' through which the ends of the sprocket chain pass. In cases where the turnnions 3' are employed, the ears 21 may be dispensed 30 with or entirely omitted from the base plate 1 and the turnnions held in bracket members 26' shown in Fig. 10 of the drawings, the bracket 26' being bifurcated and formed 35 with an annular seat 25' in which the turnnions are held by means of a thumb screw 27.

It will thus be observed that the spark 40 control and the throttle are embodied in the steering wheel proper, confining all the parts to a small sphere within convenient and ready reach of the operator.

What I claim is:—

1. A steering mechanism for motor boats, 45 including a base plate formed with downwardly projecting perforated ears, a steering wheel supported from the base plate, brackets for supporting the base plate, each of said brackets including an arm having a bifurcated perforated outer end, said ears of the base plate being received in the furcations of the ears, and a thumb screw passed through the perforations of the bracket arm and the ears of the base plate. 50

2. A steering mechanism for motor boats, 55 including a base plate, a collar carried by the base plate and depending therefrom, an arbor tube having one end in threaded engagement with said collar, a bearing sleeve arranged on the interior of the arbor tube at the base thereof, a screw passing through the collar, the arbor tube and the bearing sleeve, a controller tube in engagement with the bearing sleeve, a controller rod mounted 60 in the controller tube, operating levers for

the controller tube and controller rod, a steering wheel, a sprocket surrounding the arbor tube and having an upwardly extending annular flange, and an outer tube secured to the steering wheel and to said 70 flange of the sprocket wheel.

3. A steering mechanism for motor boats, including a base plate, a collar carried by the base plate and depending therefrom, an arbor tube having one end in engagement 75 with the collar, a bearing sleeve arranged on the interior of the arbor tube at the base thereof, means for rigidly uniting the arbor tube and the sleeve to the collar, a controller tube in engagement with the bearing sleeve, 80 a controller rod mounted in the controller tube, a steering wheel, a sprocket surrounding the arbor tube, means for connecting the sprocket to the steering wheel, and means carried by the steering wheel for operating the controller tube and controller 85 rod.

4. A steering mechanism for motor boats, including a steering wheel, throttle control means, spark control means, and means for 90 operating each of said means carried by the steering wheel and including a lever secured to the throttle control means, a lever secured to the spark control means, a sector common to each of said levers, said sector being 95 formed on its opposite sides with depressed seats, a ball carried by each lever to engage in said seats, and a spring also carried by each lever and arranged to the rear of the ball to hold same in engagement with the 100 seats.

5. A steering mechanism for motor boats, including a base plate, a collar rigidly carried by the base plate and depending therefrom, an arbor tube arranged to engage the 105 collar on the interior of same, a bearing sleeve on the interior of the arbor tube at the base thereof, means to rigidly unite the bearing sleeve and the arbor tube to the collar, throttle control and spark control 110 means arranged one within the other and being supported by the bearing sleeve, a sprocket surrounding the arbor tube, a steering wheel, and a tube connected to the steering wheel and to said sprocket and surrounding said arbor tube. 115

6. A steering mechanism for motor boats, including a steering wheel, a tube secured to the steering wheel, means adapted to connect the lower end of the tube to the rudder, 120 spark control and throttle control means arranged on the interior of the tube, a lever connected to the spark control means, and a lever connected to the throttle control means, a sector having depressed seats common to each of said levers, and spring pressed balls carried by the levers and adapted to engage in said depressed seats. 125

7. A steering mechanism for motor boats, including a base plate, an arbor tube rigidly 130

secured to the base plate, a control tube and a control rod to govern the spark and throttle arranged on the interior of the arbor tube, a sprocket surrounding the arbor tube 5 and having an upwardly projecting flange, a steering wheel, and a tube surrounding said flange of the sprocket and rigidly connected to said steering wheel.

8. A steering mechanism, including a base 10 plate having a collar rigid therewith, an arbor tube engaging on the interior of the collar and rigidly secured thereto, a bearing sleeve on the interior of the arbor tube rigidly secured thereto, a controller element 15 on the interior of the bearing sleeve, a sprocket wheel surrounding the arbor tube and rotatable with respect thereto, a steering wheel, and means secured to the steering wheel and to said sprocket whereby ro-

tation of the steering wheel will cause corresponding movement of the sprocket. 20

9. A steering mechanism including a base plate, an arbor tube rigidly secured to the base plate, a controller tube on the interior 25 of the arbor tube, means to provide a bearing for said controller tube carried by the arbor tube, a controller rod on the interior of the controller tube, a sprocket wheel rotatably surrounding the arbor tube, and a steering wheel rigidly connected to the 30 sprocket.

In testimony whereof I have hereunto set my hand in presence of two subscribing witnesses.

JOHN A. SEELY.
